UNITED STATES PATENT OFFICE

EDWARD B. WILDER, OF ST. LOUIS, MISSOURI

KITE

Application filed November 5, 1927. Serial No. 231,282.

This invention relates to kites, and the principal object of the invention is the provision of a kite that is so constructed that it will maintain itself automatically in a 5 position of stability without the use of a bridle or a tail when it is being floated in the air with its string under tension. Otherwise stated, it is the purpose of the invention to provide a kite that will adjust itself to the 10 wind pressure and eliminate the diving that is usual in the flying of kites.

Another object is to provide a kite of the knockdown type that may be handled and shipped in a partly disassembled and collapsed state so as to save space and, also, to prevent breakage during storage or transportation, and that may be readily assembled without the use of tools preparatory to flying the kite.

20 Another object is the provision of means for reinforcing the sail or sheet at the point thereon adapted to receive the string.

Other objects and advantages, more or less ancillary to the foregoing, will appear in the 25 course of the following description of two embodiments of the invention that have been selected for the purpose of illustration only and not in a limiting sense.

In the accompanying drawings forming 30 part of this specification, in which like numbers of reference denote like parts wherever they occur,

Figure 1 is a transverse sectional view, taken on the line 1—1 in Figure 3, of one form 35 of the invention;

Figure 2 is a lateral edge view of the same;

Figure 3 is a rear elevation of the same kite;

Figure 4 is a transverse sectional view, 40 taken on the line 4—4 in Figure 6, of another form of the invention;

Figure 5 is a sectional enlargement view taken on the line 5—5 in Figure 6;

Figure 6 is a rear elevation of the kite of 45 Figures 4 and 5; and

Figure 7 is a fragmentary rear elevation of the same as it appears with the frame removed therefrom.

The kite comprises a sail sheet 1 of paper 50 or other suitable material, and a frame 2 for

spreading the sheet 1. The sheet 1 is preferably of the usual polygon shape, that shown in Figures 1 to 3, inclusive, being six-sided, while that shown in Figures 4 to 7, inclusive, has four sides. In either case, the marginal 55 portions 3 of the sheet 1 are lapped over and pasted or otherwise secured to the rear side of the sheet so as to cover and secure therebetween a string 4 that follows and so reinforces the edges of the sheet 1. The marginal portions 3 do not, however, overlap at the corners 5, so that the string 4 is exposed thereat so that it can be engaged by the frame 2, as will 60 presently appear.

The frame 2 preferably comprises a plurality of crossed struts, such as light slender sticks of wood, one stick 6 of which extends laterally and is wider and thinner than the other stick or sticks so as to be more flexurally resilient from front to rear than the latter, which may have the usual degree of rigidity of kite sticks. The form of Figures 4 to 7, inclusive, embodies a longitudinally extending stick 7 that is more rigid 75 than and intersects the stick 6; while the form of Figures 1 to 3 inclusive, utilizes two rigid sticks 7 that intersect one another and the stick 6 at a common point. The ends of the sticks 7 are slotted laterally as at 8 to 80 straddle and receive the detached and exposed portions of the string 4 at the corners 5 of the sheet 1. The cross stick 6, being too thin to be slotted laterally, is preferably provided with transversely extending 85 V-shaped notches 9 in its ends to receive the string 4. The lengths of the respective sticks with relation to the length of the string 4 is preferably, though not necessarily such that when the ends of the sticks are engaged 90 with the respective corner portions of the string, the string will be taut and the stick 6 will be bowed so as to present a convex side toward the sheet 1. The sticks 7, being more rigid than the stick 6, will be flexed 95 very little when the sticks closely overlie one another at their intersection, so that the face of the kite will be convex, the convexity being much greater in the direction of the kite's lateral extension. In the case of the four 100

sided kite, there may be practically no flexure of the longitudinally extending strut 7.

A kite-line or flying string 10 passes through the sheet 1 from the front thereof and is tied around the several sticks at their intersection, the knot being brought to the middle of the front of the sticks. It is, of course, necessary to make a hole 11 in the sheet 1 opposite the point of intersection of the sticks for the passage of the flying line 10 therethrough. To prevent the sheet from being torn by the string at the edges of the hole 11, and, also, to insure that the string emerges through the sheet 1 at the point of intersection of the sticks, a reinforcing annular patch or stay 12 of heavier paper or other suitable material is preferably pasted on the sheet 1 at the point through which the hole 11 is to be made in the sheet 1. The patch 12 is preferably placed on the rear side of the sail 1 so that it may, also, serve to locate the point of intersection of the sticks.

The cross-stick 6 is wide enough to hold the kite paper or sheet 1 in position with an ordinary wind; but, being thinner than the longitudinally extending stick or sticks 7, the cross stick 6 is sufficiently flexurally resilient from front to rear to bow or yield back at the ends of the stick 6 to an extent depending on the pressure of the wind that is exerted against the face of the kite, thereby making the kite adjust the convexity of its face automatically to suit the wind pressure and so prevent the diving that is usual in the flying of kites. The kite is, also, so proportioned as to be balanced correctly, and may be flown without a tail, except during strong or gusty winds, for the convex face of the kite tends to steady it and prevent undue swaying. If a tail be used, it is attached to the lower end as indicated by the dotted lines at 13. If desired, the cross-stick 6 may be formed initially so that it is normally curved, at least, to a slight extent, so that the curvature of the cross-stick may be facilitated during the assembly of the kite.

It will be observed that when the sail 1 and the frame 2 are disassembled from one another, the sail 1 and its included string 4, on account of their flexibility, may be rolled into compact form; and the sticks 6 and 7 likewise may be placed together to occupy a minimum of space, thereby facilitating shipping and handling of the kite. To assemble the kite, it is merely necessary to insert the cross-stick 6 so that its notched ends engage the string 4, after which the sticks 7 may be inserted in like manner, and the flying string 10 attached as hereinbefore explained.

Having thus fully described this invention, I hereby reserve the benefit of all changes in form, arrangement, order, or use of parts, as it is evident that many minor changes may be made therein without de-

parting from the spirit of this invention or the scope of the following claims.

I claim:

1. A kite comprising a sail sheet and a frame consisting of crossed struts of which one is more flexible transversely of the kite than the others, and said sail sheet being attached to the ends of all of the struts. 70

2. A kite comprising a sail sheet, a frame consisting of crossed struts of which one is more flexible than the others, said sail sheet being attached at its edge to the ends of all of the struts, and a flying line attached to the frame at one point only. 75

3. A kite comprising a sail sheet, a frame consisting of crossed struts of which one is more flexible than the others, said sail sheet being attached at its edge to the ends of all of the struts, and a flying line attached to the frame at one point only and said attaching point being coincident with the point of intersection of the struts. 80

4. A kite comprising a sail sheet, and a frame consisting of crossed longitudinal and transverse struts, said sail sheet being attached to all of said struts, and the transverse strut being more flexible than the longitudinal struts. 85

5. A kite comprising a sail sheet and a frame consisting of crossed struts of which one is wider and thinner than the other and the said sail sheet being attached at its edge to the ends of all the struts. 90

6. A kite comprising a sail sheet and a frame consisting of crossed struts of which one is wider and thinner and shorter than the other and the said sail sheet being attached at its edge to the ends of all the struts. 95

In testimony whereof I hereunto affix my signature.

EDWARD B. WILDER.
